UNITED STATES PATENT OFFICE.

JOHANN HEINRICH LUDWIG NAUWERCK, OF ST. LOUIS, MISSOURI.

DESIGN FOR A MEDAL.

SPECIFICATION forming part of Design No. 16,219, dated September 1, 1885.

Application filed April 12, 1884. Term of patent 14 years.

To all whom it may concern:

Be it known that I, JOHANN HEINRICH LUDWIG NAUWERCK, of St. Louis, in the county of St. Louis and State of Missouri, have invented and produced a new design, the character of which is fully set forth in the following specification, reference being had to the accompanying photographs.

The leading features of my design, as shown, 10 are the representation of a crown encircling the shaft of an anchor on a plain panel within a nimbus on one side of an annular medal, and a horseshoe with projecting nails and a clover-leaf in a circular plain field on the other.

15 Figure 1 is a view of the obverse and Fig. 2 a view of the reverse side of the medal embodying my design.

The medal is circular in outline, and has on its obverse side the design illustrated in Fig. 20 1 of the accompanying drawings, wherein the figure consisting of a crown located in a panel presented by an encircling nimbus. The reverse side of the medal has thereon another

feature of my design, as represented in Fig. 2 of the accompanying drawings, the said feature consisting of a horseshoe, on the left side of which are several projecting nails, the representation of a clover branch being so arranged relative to the shoe that the leaf portion of said branch rests on the right-hand portion of said shoe.

I claim—

The design for a medal herein described, the same consisting of the representation of a crown encircling the shaft of an anchor on a plain panel within a nimbus on one side of the annular medal, and a horseshoe with projecting nails and a clover leaf in a circular plain field on the other, substantially as shown and set forth.

Hot Springs, Arkansas, March 9, 1884.

JOHANN HEINRICH LUDWIG NAUWERCK.
